UNITED STATES PATENT OFFICE

148,283

DESIGN FOR A KNIFE RACK

Emerson E. Case, Perry, N. Y., assignor to Robeson Cutlery Company, Inc., Perry, N. Y., a corporation of New York

Application March 11, 1946, Serial No. 127,329

Term of patent 14 years

(Cl. D44—29)

To all whom it may concern:

Be it known that I, Emerson E. Case, a citizen of the United States, residing in Perry, in the county of Wyoming and State of New York, have invented a new, original, and ornamental Design for a Knife Rack, of which the following is a specification, reference being had to the accompanying drawings, forming part thereof.

Fig. 1 is a side elevational view of a knife rack showing my new design;

Fig. 2 is a front elevational view of the same;

Fig. 3 is a top plan view of the same;

Fig. 4 is a vertical sectional view through the same, the section being taken substantially on the line 4—4 of Fig. 1; and

Fig. 5 is a perspective view of the same.

I claim:

The ornamental design for a knife rack, substantially as shown.

EMERSON E. CASE.
